(57) **CLAIM**

The ornamental design for a handle for a battery terminal post clamp, as shown and described.

DESCRIPTION

FIG. 1 is a left side view of a handle for a battery terminal post clamp showing my new design in the open position, wherein the broken line showing is for illustrative purposes only and forms no part of the claimed design;

FIG. 2 is a left side view thereof;

FIG. 3 is a top plan view thereof;

FIG. 4 is a back elevational view thereof;

FIG. 5 is a front elevational view thereof;

FIG. 6 is a bottom plan view thereof, wherein the broken line showing is for illustrative purposes only and forms no part of the claimed design; and,

FIG. 7 is a right side view thereof.
